OIL BURNER

Lee B. Mettler, Los Angeles, Calif.

Application September 15, 1931, Serial No. 562,913

1 Claim. (Cl. 158—75)

My invention relates to burners in which oil or other combustible liquids are used as fuel.

An object of the invention is to construct and arrange an oil burner so that steam, air or any other suitable gaseous substance under pressure may be used in order to atomize the liquid fuel that is ejected from the burner, and to provide the burner integrally with means for completely regulating the supply of the atomizing agent at the 10 tip of the burner without necessitating removal of the burner from the furnace or disturbing its connections.

An object of the invention is to construct and arrange a burner so that the atomizing agent is forced by a twirling motion into the liquid fuel externally of the burner in order to maximize the atomizing effect of the agent and to cause combustion of the fuel to be as near complete as possible.

Another object of the invention is to connect 20 the supply conduits for the liquid fuel and the atomizing agent with a burner by a common element, and to arrange the connection between the burner and the element so that the burner can be quickly and easily secured to, or removed from, 25 the element.

A further object of the invention is to provide a simple, easy, understandable assembly, whereby 30 the user is able to get the highest possible atomization with very slight effort upon his part, irrespective of what kind of fuel is fed to the burner or whether such fuel is under a high pressure, say 200 pounds, or low gravity pressure, or whether 35 the atomizing agent is under high or low pressure, whether air or steam.

A still further object is to provide a novel burner whereby the fuel supplied for combustion may be preheated within the burner construction it- 40 self.

Another object of the invention is to construct 45 a novel burner of few parts, which are so arranged that the burner can not easily get out of order and so that a long life of the burner is assured.

Other objects, advantages, and features of invention may appear from the accompanying 50 drawing, the subjoined detailed description, and the appended claim.

The drawing illustrates the invention in the form I at present deem preferable.

Figure 1 is a side elevation of the oil burner, 55 as applied to, and extended through a furnace wall of which only a portion is shown in section. The yoke, by which the burner is secured to the common element between the burner and the conduits for the fuel and the atomizing agent, is shown in full lines in its burner-securing position,

and dot-and-dash lines indicate the yoke moved to a burner-releasing position.

Fig. 2 is a longitudinal axial section of the burner and its connecting means with its conduits for the fuel and the atomizing agent shown connected thereto.

Fig. 3 is an end elevation of the burner, as seen from the left in Fig. 1, and shows in mid-section a portion of the yoke and a portion of the common connecting element between the burner and the element in order to disclose clearly the pivotal connection between the yoke and the element.

Fig. 4 is a fragmental side elevation of the nozzle end of the fuel conducting tube, the view 15 being on a larger scale than Figs. 1, 2 and 3.

The burner 5 of my invention includes an inlet member 6, in which are formed passages 7 and 8, separated by a wall 9. A common conducting element 10, which is bifurcated so as to form 20 branches 11 and 12, has an end portion 13, adapted to be seated on a seat portion 14 at the top of the member 6. The branch 11 has therein a passageway 15, and the branch 12 has therein a passageway 16. These passageways lead 25 through the body of the element 10 to the end portion 13 and are separated by a wall 17. When the element 10 is seated on the seat portion 14, the passage 15 communicates with the passage 7 through an opening 18 in the seat portion, while 30 the passage 16 communicates with the passage 8 through a similar opening 19 in the seat portion, the openings 18 and 19, like the passages 7 and 8, being separated from each other by the wall 9. A gasket 20, having openings adapted to register 35 with the respective openings 18 and 19, is preferably placed on the seat portion 14 and insures a tight connection and the latter is bordered and protected by a flange 21, which, when the element 40 is seated on the seat portion, also surrounds and protects the end portion 13. A conduit 22 provided with a valve 23 and secured to the branch 11, communicates with the passage 7 and with a source of liquid fuel under pressure, and the passage 8 similarly communicates through a conduit 45 24 with a source for supplying an atomizing agent, such as steam, air or any other suitable gaseous substance, under pressure, and said conduit 24 is provided with a valve 25 to control flow of the atomizing agent.

The inlet member 6 of the burner 5 is externally threaded at the end in which the passage 8 is located. It is also internally threaded at such end in order to receive therein the threaded inner end of a nozzle member or tube 26, so that the 55

latter may be screwed to adjusted position relative to the inlet member. Pins 27 are screwed into the wall of the tube so as to form handles by which the turning of the tube to adjusted positions may be facilitated, and a packing nut 28, preferably provided peripherally with handles in the form of lugs 29, fits around the tube 26 and is adapted to be screwed externally upon an extension 6' of member 6, while a packing 30 in the 5 nut and around the tube serves to make the connection between the tube and the member 6' tight when the nut is tightened upon the member 6'. Upon the outer end of the tube 26 is screwed an atomizing nozzle member 31, the outer end of which preferably is of a conical formation so that 10 a conical seat portion 32 is formed in the nozzle and the nozzle outlet 33 is contracted and thereby adapted to concentrate the flow of the atomizing agent from the nozzle so that the agent will be directed across the flow of fuel as hereinafter 15 more fully explained to thoroughly break up and atomize the liquid fuel.

The wall 9 in the inlet member 6 has therein a threaded opening, co-axial with the tube 26 and 20 of a diameter smaller than the inside diameter of the tube, and in this opening is screwed the inner end of a tube 34, which extends through the passage 8 and through the major portion of the tube 26 so that a space A is formed between 25 the walls of the tubes 26 and 34. A fuel nozzle member 35, which is of a smaller diameter than the inside diameter of the tube 26 and the nozzle 31 is provided with a valve portion 36 at its discharge end, and has throughout its length a central opening 37, which terminates in an outlet 38 preferably of a smaller diameter than the nozzle outlet 33. This nozzle member 35 is 30 screwed upon the outer end of the tube 34 so that the member 35 extends co-axially through the tube 26 and the nozzle 31 and is adapted to be engaged at its end portion by the portion 32 of the nozzle 31 and to close the outlet 33 in the atomizing nozzle 31 when the tube 26 has been 35 adjusted relative to the member 6 a predetermined degree. At an intermediate portion the fuel nozzle 35 has on its outer periphery a number of spirally arranged ribs 39 which snugly fit the inner wall of the atomizing nozzle 31, thereby forming spiral channels 39' which give the atomizing agent a twirling motion as it leaves nozzle opening 33 to further assist in complete atomization of the liquid fuel.

The element 10 is provided on opposite sides with bosses 40, and an opening 41 is formed 40 through the bosses and the body of the element. A yoke 42 fits over the bosses at its free end 43 and a bolt 44 extends through the end portion 43 and through the opening 41 so that the yoke is thereby pivotally attached to the element 10. A nut 45 is screwed on bolt 44 in order to hold 45 the bolt in place. The yoke is so constructed, and its pivotal arrangement relative to the element 10 is such, that it is adapted to embrace the inlet member 6 of the burner 5 and swing freely 50 to or from embracing position when the member 6 is seated on the element 10. A locking bolt 46 is screwed through yoke 42 and is adapted to rest in a depression 47 in the underside of the inlet member, so that, when the member 6 is seated on the element 10, the screw is adapted to hold the element and the inlet member positively secured 55 to each other.

Preferably integral with the branch 12 and the element 10, is a supporting bracket 48, which is 60 adapted to be secured by any suitable means such

as bolt-and-nut means 49 to any suitable portion of the furnace wall B which has therein an opening 53 sufficiently large for allowing the burner to pass therethrough, so that the burner, when connected with the element 10, extends 5 through the wall into the furnace a predetermined distance.

By the construction of the inlet member 6, as described, easy access is had into the member and to each side of the wall 9 and to the passage 8. 10 In the outer end portion of the passage 7 the inlet member has preferably a threaded opening, in which is screwed a plug 54, thus also providing easy access from that end into the passage 7. 15

When the burner 5, connected with the furnace as before described, is in operation, oil will flow from the conduit 22, under control of valve 23, through the passage 15, the opening 18, the passage 7, the tube 34 and will be ejected from the fuel nozzle member 35 through the opening 38. It being assumed that the tube 26 has been adjusted so as to move the end portion 32 of the nozzle 31 slightly away from the valve portion 36 of the fuel nozzle member 35, as shown in Fig. 2, 25 the atomizing agent will flow from the conduit 24 under control of valve 25 through the passage 16, opening 19, through the tube 26, in passage 8, and passage A that is around the tube 34 and through the atomizing nozzle 31, and the spiral channels 39', and will be ejected with a twirling motion through the outlet 33 so as to cause a thorough atomizing of the oil that is ejected from fuel nozzle member.

If it is desired to increase the volume of flow 30 of the atomizing agent, the tube 26 may be turned so as to move the end portion of the atomizing nozzle farther away from the fuel nozzle, as indicated by dot-and-dash lines in Fig. 2. In order 35 to turn the tube 26, it is only necessary to loosen the packing nut 28. When the tube has been adjusted until the atomizing nozzle is in the desired position, the nut 28 is again tightened so that the atomizing nozzle is thereby securely held in adjusted position relative to the valve member. 40

If it is desired to remove the burner 5 from the element 10, the valves 23 and 25 are first closed so as to prevent the fuel and the atomizing agent from flowing to the burner. The screw 46 is then loosened, and the yoke 42 is swung to a 45 releasing position for clearing the inlet member 6, as indicated by dot-and-dash lines in Fig. 1, when the burner can be easily removed from the element 10, and withdrawn from the furnace. With the yoke in the dot-and-dash line position, 50 as shown in Fig. 1 the burner is just as easily connected with the element and is locked thereto when the yoke has been swung to its adjusted position relative to the inlet member 6 and the screw 46 tightened.

From the foregoing it is evident that the burner of my invention causes an efficient and thorough atomizing of the liquid fuel and, consequently, a complete combustion thereof. It is also evident that the element 10 serves a most useful purpose 55 as a common carrier for the oil and the atomizing agent from the conduits 22 and 24 to the burner, and that, by the construction of the element and the construction of the inlet member 6 of the burner, a considerable saving of time is effected in connecting the burner with, or disconnecting it from, the conduits, as there will be no necessity of removing or disturbing the supply 60 connections.

It will also be evident from the foregoing that 75

by reason of the atomizing agent passing around the fuel delivery tube 34, particularly when steam is used as an atomizing agent, that the liquid fuel will be preheated before delivery at the fuel 5 nozzle and thereby further aid in complete atomization.

By constructing the atomizing and fuel nozzles with a conical formation as shown in Fig. 2, the atomizing agent will be delivered from its nozzle 10 in a direction that will tend to force the atomizing agent across and through the liquid fuel being delivered from the fuel nozzle thereby causing a thorough breaking up of the fuel and intermingling of the fuel and atomizing agent to 15 a state of complete atomization.

I claim:

An oil burner comprising a hollow inlet member having a seat portion and provided with an 20 interior wall which has therein an opening and is so arranged that a passage for liquid fuel is formed on one side of the wall and that a passage for an atomizing agent is formed on the other

side of the wall, said passages opening through 5 said seat portion; a tube provided externally at one end with a valve seat portion, and secured at its other end to the opening in the wall; a nozzle member surrounding the tube so as to allow the atomizing agent to pass through the 10 nozzle member and having therein at one end a valve portion which is adapted to be seated on said valve seat; means adjustably connecting the nozzle member to the inlet member so as to cause the nozzle member to communicate with the passage for the atomizing agent and to allow the nozzle member to be moved with its 15 valve portion toward, or away from, the seat portion of the tube; and a packing nut, which fits around the means connecting the nozzle member to the inlet member and is adapted to hold packing means therein, said nut being 20 adapted to be secured on the inlet member so as to tighten the packing over the means connecting the nozzle member to the inlet member.

LEE B. METTLER.
